UNITED STATES PATENT OFFICE

HARRY ZWERLING, OF BROOKLYN, NEW YORK

INSTALLATION FOR SUPPLYING AND CIRCULATING HEATED OR COOLED AIR

Application filed April 21, 1926. Serial No. 103,599.

This invention relates to ventilating systems and more particularly is directed to improved installations for supplying and circulating heated or cooled air in dwellings and for other purposes.

One object of the invention is to provide in an installation of the character described, an improved air heating and cooling apparatus which shall be relatively small, compact, and adapted to include a steam boiler of any standard make to form a self contained unit.

Another object of the invention is to provide an improved installation of the character described adapted to be used with or without forced circulation whereby the heating and cooling effects of the air may be readily controlled over a wide range of desired temperatures.

20 A further object of the invention is the provision of an installation of the character described which is constructed of few and simple parts, relatively cheap to manufacture, easy to operate, and practical and efficient to a high degree in use.

Other objects and advantages will in part be obvious and in part hereinafter pointed out.

The invention accordingly consists in features of construction, combination of elements and arrangement of parts which will be exemplified in the construction hereinafter discussed of which the scope of application will be indicated in the following claims.

35 In the accompanying drawing in which a possible embodiment of the invention is shown:—

Fig. 1 is a side elevational view, partly in section, showing an installation for supplying and circulating heated and cooled air embodying the invention.

Figs. 2 and 3 are cross sectional views taken on lines 2—2 and 3—3 in Fig. 1, respectively.

45 Fig. 4 is a fragmentary cross-sectional view showing in detail the construction of the header and tubes of the radiator.

Fig. 5 is a fragmentary side elevational view, partly in section showing a modified form of the invention.

Referring in detail to the drawing, 10 denotes a steam boiler which may preferably be of any standard construction having a water jacket 10^a about the furnace thereof. Said boiler may be connected with a suitable 55 water supply (not shown) through feed pipe 11 and may be equipped with the usual feed water sight and steam pressure gages 13 and 12, respectively, the latter preferably being positioned over the furnace and "clean- 60 out" doors 14 and 15 as shown in Fig. 1. To control the air supply to the boiler furnace a draft damper 16 may be provided in an air duct 17 at the rear of said boiler and if desired a regulator 18 may be provided to automatically open and close the damper 16 and control the fire in the boiler furnace according to the steam pressure generated, in a well understood manner.

65 Suitably supported over the boiler 10, there is a radiator 21 having spaced headers 22 which connect with the usual boiler steam outlet and drain return fittings 19 and 20, respectively, said radiator being positioned to permit making said pipe connections 70 therefrom to the boiler as short as possible so that a constant supply of steam to the radiator may be maintained with a minimum amount of heat. The radiator 21 comprises besides the spaced headers 22, a plurality of 75 horizontally disposed tubes 23, which interconnect them preferably in staggered rows. Said headers may be of any suitable construction and are preferably made of sheet metal, each header having an outwardly concave backing member 22^a and a tube sheet 22^b. As seen from Fig. 4, the edge portion of said tube sheet and backing member are interfoldingly clamped together to form a tight joint 24, the seams of said joint preferably 80 being reinforced by welding or brazing. The tubes 23 may be secured to the tube sheet 22^b in any well understood manner, as by rolling said tube ends and brazing and welding the seams at the rolled joints.

85 Surrounding the boiler 10 and radiator 21 is a casing 25, the walls of which are spaced from the boiler but closely fit about the radiator headers 22 and tubes 23 as shown in Fig. 2. Said casing extends above the radi- 90 95 100

ator 21 to provide a chamber which may be divided into compartments 26 by a suitable partition 27, said compartments communicating with a plurality of distributing flues 28. For minimizing the heat radiation losses 5 from the casing surfaces, the casing is preferably jacketed with a heat insulating material 40. As shown in Figs. 1 and 2 the air supply duct 17, for the boiler furnace communicates with the chamber compartment 26 over the 10 radiator 21 so that heated air is supplied through said duct to the boiler furnace for increasing the efficiency of combustion, as is well understood.

15 To provide forced circulation of air through the casing 25, a blower 29 driven by any suitable means such as motor (not shown) may be provided, the blower outlet 29^a being connected with the bottom portion 25^a of the casing 25. The blower intake 29 connects 20 with one end of any junction duct 30, the other end of said duct being connected to receive the recirculating air from a preheating box 31. There is also provided a branch 25 30^a controlled by a damper 32 from said duct to the casing portion 25^a for by-passing the blower 29, and a vent 30^b, controlled by a damper 33, as shown in Fig. 3.

30 The wasted heat passing from the boiler furnace, through a pipe 34 having a damper 34^a to the chimney 35 may be utilized by surrounding a suitable length of said pipe by the box 31 for preheating recirculation air received from a return flue 37 prior to passing 35 said air through the junction-duct 30 to the casing 25.

35 The operation of the ventilating system embodying the invention will now be described. Assuming the apparatus arranged 40 as shown in Figs. 1, 2 and 3 with the distributing flues 28 or branches thereof carried to the different rooms or floors of the dwelling and the return flue 37 preferably extending down from a central part of said dwelling, the boiler 10 is put in operation to generate steam. If the weather is only moderately 45 cold forced circulation of heated air can be dispensed with so that the blower 29 can shut down and the by-pass damper 32 opened, that is moved to the dotted line shown in Fig. 3. The air in the casing 25 about the boiler 10 and the radiator 21 will be heated and will rise up through the distributing flues 28 and preheated recirculating air will be drawn 50 into the casing 25 from the box 31, the junction duct 30 and return flue 37. In mildly cold weather the preheated recirculating air may be cut off by opening the vent damper 55 33 and shutting off the passage to the pre-heating box 31 and return flue 37, as shown in the dotted line position of the damper 33 in Fig. 3. The air then passes into the junction duct 30 at the vent 30^b through the by-pass branch 30^a then into the casing 25.

60 65 When the weather is cold forced circulation

of heated air may be required in which case, power is applied to the blower and the damper 32 and 33 positioned as shown in full lines in Fig. 3. The recirculating air in the return flue 37 is thus caused to be drawn through the box 31, preheated and forced into the casing 25. Then the air, in passing around the boiler 10 and through the radiator 21, is heated to a desired temperature and is distributed through the flues 28.

70 75 For expelling non-condensable vapors and gases from the radiator 21 when the system is used to supply heated air, an air valve 50 of any standard construction may be provided and installed in the system in the well understood manner. To adapt the ventilating system for supplying and circulating cooled air during warm and hot weather, there is extended horizontally from an upper portion of one of the radiator headers 22 to a drain 80 or sewer (not shown), a pipe 51 having a shut-off valve 52. To this pipe 51 between the said header 22 and the valve 52, the air valve 50 provided with a suitable cock 53 may be connected.

85 90 In using the ventilating system to supply cooled air, the cock 53 is closed to prevent leakage at the air valve 50 and a valve 54 provided in the return drain line of the boiler connected with the fitting 20 is shut to cut off the direct passage from the adjoining header 22 to the boiler. Now on opening wide the valve 52 and turning on the water supply to trickle or flow slowly through feed water pipe 11, the boiler jacket 10^a and radiator 21 may be filled and the water kept in constant circulation therethrough at a relatively low water pressure. Operating the blower 29 is effective to cause the air which is cooled by contact with the boiler jacket 95 and the radiator water cooled surfaces to be distributed through the flues 28. The air may be recirculated or fresh air may be used by setting the dampers of the junction duct 30 as is readily understood from Fig. 3.

100 105 Where the furnace equipment is installed in cold surroundings and it is desirable to utilize portion of the heat radiated from the boiler jacket to keep the neighboring water pipes or the like from freezing during cold weather, the modified form of construction shown in Fig. 5 may be used. Here the casing 122 is mounted on top of the boiler 10 so that the surface of the jacket of the latter 110 serves to supply the necessary heat. Thus in this modified form of construction, the air from the blower and junction duct enters the casing 122 through the opening 122^a, and the radiator 21 provided with radiating surface 115 sufficient to heat or cool the air within the desired range of temperature.

120 125 It will thus be seen that there is provided a ventilating system in which the several objects of this invention are achieved and

which meet the conditions of practical use and to give unusual satisfaction.

As many other possible embodiments might be made to the above invention and as various changes might be made in the embodiment set forth, it is to be understood that all matters herein set forth or shown in the accompanying drawings is to be interpreted as illustrative and not in a limiting sense.

Having thus described my invention I claim as new and desire to secure by Letters Patent:

1. An apparatus of the character described including a steam generating means, spaced means for radiating the heat in the steam generated, a casing for enclosing said generating and radiating means, means for supplying air to said casing, the walls of said casing being spaced from the generating means to provide a passage for the air about the latter, said casing walls being fitted closely about the radiating means to direct all the air from said passage through said radiating means, and an air supply junction duct having a plurality of branches connected to said passage.

2. An apparatus of the character described including a heat source having a water and steam jacket, a radiator formed with through passages heated by steam from the jacket, a casing enclosing said source and radiator, said casing forming a duct about said jacket, said duct and passages being positioned to receive a flow of air from one to the other in one direction, a blower for supplying the air connected with said duct, and means for by-passing said blower whereby the air supplied is varied.

3. A ventilating system of the character described, a steam generating means, a steam radiator connected to generating means, a casing for enclosing said means and radiator, means for supplying air under various pressures to the casing, means for preheating the air prior to supplying same to casing, said preheating means receiving heat from said generating means, and flues extending from said casing for distributing the air after being heated by said generating means and radiator.

4. In a ventilating system of the character described, a boiler, a radiator heated by steam generated in the boiler, said radiator comprising a pair of spaced headers interconnected by rows of parallelly aligned tubes, one of said headers being connected to the boiler steam outlet fitting and the other header to the boiler drain fitting, a casing enclosing the boiler and radiator, and means for supplying air into said casing for passage through the latter, said headers being positioned in close proximity to the walls of said casing for directing the air in the casing transversely with respect to the length of said rows of tubes.

5. A device of the character described for

supplying and circulating heated or cooled air comprising a casing, a steam generator including a water jacket within the case, a radiator in said casing connected to said jacket adapted to heat the air passing through the casing, means for converting said jacket and radiator into a heat absorbing means to cool the air, means for supplying air from a plurality of sources, and means for varying the air pressure supplied from one of said sources.

6. An apparatus of the character described including a heat source, a water and steam jacket surrounding said source, a radiator having through passages, said radiator having an inlet and return connection for circulating therethrough steam received from the jacket, a casing enclosing said jacketed source and radiator, said casing being spaced from said jacket to form a passage therebetween communicating with said radiator passages, means for supplying air to said casing passage, a water supply connected to said jacket, closure means in one of said radiator connections for cutting off communication therethrough with said jacket, and water draining means on said radiator spaced from said jacket to permit continuous flow of water through the jacket and radiator for converting the latter into a heat absorbing means to cool the air in the passages.

7. In a ventilating system of the character described, a boiler, a radiator heated by steam generated in the boiler, said radiator comprising a pair of spaced headers interconnected by rows of tubes, one of said headers being connected to the boiler steam outlet fitting and the other header to the boiler drain fitting, a valve interposed between said headers and said boiler fittings for cutting off the communication therethrough, a casing enclosing the boiler and radiator, means for supplying air into the casing, a water supply connected to said boiler, and water draining means on one of said headers to permit a continuous flow of water through the headers and tubes for converting the radiator into a heat absorbing means for cooling the air passing between the tubes.

In testimony whereof I affix my signature.

HARRY ZWERLING.
